UNITED STATES PATENT OFFICE.

FERDINAND MORA CANDA, OF NEW YORK, N. Y.

METHOD OF ROLLING BALLS.

Application filed April 25, 1924. Serial No. 708,990.

To all whom it may concern:

Be it known that I, FERDINAND MORA CANDA, a citizen of the United States, residing at New York city, in the county of New York and State of New York, have invented certain new and useful Improvements in Methods of Rolling Balls, of which the following is a specification.

My invention relates to a method of forming metal balls for use especially in grinding or pulverizing machines.

In ball rolling machines usually employed, a series of balls are formed simultaneously from a heated rod by passing the rod between a grooved roll and a correspondingly grooved shoe or die plate. As the ribs or ridges between the grooves cut into the hot rod-blank, the metal displaced by the ribs is caused to flow into the spaces of the grooves and each ball section begins to assume a spool shape. Under these conditions it is difficult to form a ball without leaving an annular groove. Again, if the metal of the rod-blank is very hot, the metal has a tendency to "spin," with the result that a central cavity is formed in the ball.

The object of my invention is to provide an improved method of rolling balls from rod-blanks which will overcome the defects of prior methods above specified and produce balls having solid cores and substantially free from surface irregularities, such as grooves, creases and other defects.

In the following detailed description I shall refer to the accompanying drawings, in which—Figure 1 is a vertical transverse sectional view of a ball rolling machine embodying my invention; Fig. 2 is a vertical sectional view on the line 2—2 of Fig. 1; Fig. 3 is a fragmentary detail view on the line 3—3 of Fig. 1; Figs. 4, 5, 6 and 7 are fragmentary views to illustrate the various stages in the formation of the balls as viewed respectively on the lines 4—4, 5—5, 6—6, and 7—7 of Fig. 1; Fig. 8 is an illustrative view to show the partially formed balls in the blank as it is about to emerge from the upper roll; Fig. 9 is an illustrative view showing the blank just after it has entered the second pass between the lower roll and its shoe; and Fig. 10 is an illustrative view showing the finished ball as it is about to emerge from the second pass.

In rolling balls from rods, it is evident that the rods must be smaller in diameter

than the diameter of the balls. To accomplish the proper finishing and perfecting of the balls near the end of the rolling operation, the material from which the ball is rolled should approximate very closely to the diameter of the finished ball and necessarily the grooves of the roll and the shoe must be confined to a semi-circular shape. I have found that I can eliminate the causes which have heretofore resulted in the imperfections in the finished balls and can produce much more perfect balls by providing a preliminary or "roughing" pass in which the rod is formed into a connected series of ball elements roughly approximating the ball shape and then subjecting this shaped connected series of ball elements to the finishing operation between a second roll and shoe. I am thereby enabled to employ grooves of an entirely different shape in the roughing pass from those of the finishing pass. Moreover as the rod is grooved about two-thirds of the way through in the preliminary pass, less space is required between the roll and the shoe in the finishing pass and the progress through the latter may therefore be made more gradual which contributes to a greater accuracy and perfection in the finished product.

The grooved rolls 10 and 12 of the upper and lower passes respectively are carried by shafts 14 and 15 which are suitably driven and are geared to rotate in opposite directions. In the methods of rolling spherical balls heretofore employed the rod or bar from which the balls are formed, is subjected throughout the entire rolling operation to the action of grooves that are substantially semi-circular with the resulting defects and imperfections in the finished balls above pointed out.

I have found that I can compact the metal and maintain it solid throughout, free from internal flaws when it is forced to flow into the grooves as the ribs cut into the metal, by so shaping the grooves in the roll 10 and shoe 16 of the preliminary or roughing pass that the sides of the grooves exert pressures toward the center of the ball element. To this end I make the grooves V-shape with the apex cut off or flattened so that the pass is substantially hexagonal, as shown in Fig. 4. It will be seen that as the ribs cut or bite into the hot metal rod or bar 20, the displaced metal which flows up into the grooves

is constantly pressed toward the center of the ball element 20^a by the inclined sides of the grooves. This prevents any tendency of the metal to spin and maintains the metal 5 solid throughout.

- As the metal continues to flow into the grooves under the impelling action of the entering ribs, there is a tendency to cause the ball elements to become spool shape with 10 a central annular groove which is difficult to remove in the subsequent rolling and which has heretofore caused imperfections in the finished balls. To obviate this difficulty I so proportion the grooves that the 15 flat central portion bears against the central part of the ball-element while the metal is still flowing into the groove and also position the oblique sides of the groove within the circumference which will be assumed by 20 the finished ball. I have indicated in Fig. 5, by broken lines the circumference of the finished ball 20^b. It will be observed that the slanting sides of the groove encroach upon the space which would be occupied by 25 the finished ball. This causes the metal to be pressed around the central belt and prevents or eradicates any groove that would otherwise form in the ball. Accordingly as the blank emerges from the preliminary 30 or roughing pass, the ball elements 20^a form substantially double cones with their bases joined by a circular band. The metal of the rod or bar has been cut about two-thirds of the way through so that the ball elements 35 are connected into a longitudinal series by short core parts 20^c as indicated in Fig. 6. Inasmuch as the metal fills the groove as it nears the end of the roughing pass the center and sides of the groove of 40 the roll exert a kneading action upon the metal tending to push a surface ridge around the ball element and consequently there will be a slight crease 20^d in the ball elements as they roll over the transfer slide 45 23 between the two passes. When the blank enters the second pass the oppositely rotating roll 12 will force the metal of this crease back and smooth it out completely.

The grooves of the finishing roll 12 and 50 coacting shoe 18 are approximately semi-

circular in contour as indicated in Figs. 6 and 7. Inasmuch as most of the cutting action has taken place in the roughing pass and the ball elements approximate their spherical shape, the initial space between 55 the finishing roll 12 and its shoe 18 is only sufficient to receive shaped series of ball elements and the variation throughout the second pass may be very gradual. After the balls have separated from each other in the 60 latter part of the finishing pass they are still subjected to the smoothing action of the grooves in which they then fit closely. This is an important improvement in ball rolling machines and contributes materially to the 65 excellence of the finished balls.

I claim:—

1. The method of forming metal balls, which comprises axially rolling a heated metal bar and grooving it into a longitudinal series of connected elements angular in section, and subjecting said connected series of elements while still hot to a second rolling operation which transforms said elements into separate spherical bodies. 75

2. The method of forming metal balls, which comprises axially rolling a heated rod or bar, and grooving it into a connected series of elements of cylindrical frustro-conical configuration, compressing said elements 80 upon a diameter perpendicular to and oblique to the axis of said series of elements to compact the same, and subjecting said series while still hot to a second rolling operation which separates the elements and molds 85 them into spherical shape.

3. The method of forming metal balls which comprises axially rolling a heated metal bar and grooving it into a connected series of elements of oppositely directed 90 conical conformation united at their ends, while maintaining the entire peripheral surface of the metal under centripetal compression and subjecting the metal while still hot to a second axial rolling operation which 95 transforms said series of connected elements into a corresponding number of separate spherical bodies.

In testimony whereof I affix my signature.
FERDINAND MORA CANDA.
